BUFFER MEANS

Herbert L. Bone, Forest Hills, and Kenneth J. J. McGowan, Pittsburgh, Pa., assignors to Westinghouse Air Brake Company, a corporation of Pennsylvania

Original application November 27, 1948, Serial No. 62,328. Divided and this application August 16, 1949, Serial No. 110,506

2 Claims. (Cl. 267—1)

1

The present invention relates to a retarding mechanism, and more particularly to a hydraulic buffer for a treadle operated circuit controller.

This is a division of our copending application bearing Serial No. 62,328, filed on November 27, 1948, now abandoned, for Control Apparatus.

Treadle operated circuit controllers for railway way operation to initiate or control signal equipment are usually provided with retarding or buffer means to prevent successive operation of the controller by the train wheels after the first actuation thereof by the initiating train wheels. While such controllers have been provided with resiliently mounted treadles, or with resilient treadles, the shock of impact of the train wheels as the treadle is depressed is transmitted to the buffer mechanism of the controller, particularly in instances of fast moving trains. The piston of the buffer is thereby subjected to quick movement, the movement being abruptly halted by the abutment of the piston with the piston stop within the cylinder. The shock of piston impact and the excessive pressures developed by the sharp movement of the piston will cause damage to the buffer mechanism.

An object of our invention is to provide a hydraulic buffer in which the shock of the sudden stop of the piston by the cylinder is absorbed.

Another object of the present invention is to provide a hydraulic buffer in which the maintenance of the oil level in the buffer housing is not dependent upon the integrity of any seals between the moving parts.

Still another object of our invention is to provide a hydraulic buffer in which an expansion chamber is formed above the level of the hydraulic fluid to provide a cushioning effect should excessive pressures be developed due to a sharp piston movement.

Yet another object of this invention is to provide a hydraulic buffer of the character indicated which shall consist of few and simple parts, relatively inexpensive to manufacture, which shall be positive in its operation, have a large variety of application and yet be practical and efficient to a high degree in use.

Other objects of the invention will in part be obvious and in part hereinafter pointed out.

The foregoing objects of the invention are accomplished by providing a two-part housing for the buffer mechanism, one part at a slightly higher level than the other. The lower part or section of the housing forms the cylinder of the buffer, the piston being movable therein. A spring is provided for biasing the piston to a normal or inactive position against a stop.

2

A check valve on the piston permits longitudinal movement of the piston within the cylinder against the action of the spring. The piston is pivoted to an arm passing from the lower section into the upper section, the arm being fixed to a shaft journaled through the upper section of the housing. A frusto-conical spring disc is provided for one end of the piston to absorb the shock of sudden stopping of the piston by the cylinder stops.

The housing of our buffer mechanism is provided with a filler plug well below the level of the buffer actuating shaft. The level of the hydraulic fluid will be determined by the level of the filler plug. This fluid level will be above the cylinder but below the level of the actuating shaft. The air space in the housing above the fluid level forms an expansion chamber for the fluid and the air trapped therein will provide a cushioning effect for any quick movement of the piston.

In the accompanying drawings forming a part of this specification in which one of the various possible illustrative embodiments of our invention is shown, and wherein the same reference characters designate corresponding parts throughout the two views.

Fig. 1 is a vertical cross-sectional view of our buffer mechanism forming a part of a treadle operated circuit controller, while

Fig. 2 is a fragmentary sectional view of the treadle and operating shaft.

Referring now in detail to the drawings, the numeral 10 designates a buffer embodying our invention. The buffer 10 as herein illustrated is incorporated into a track circuit controller 11 more fully detailed in the aforesaid parent application. The track controller 11 is enclosed in a housing 12 adapted for mounting on the gauge side of a track rail 13 by means of clip bolts 14, clips 15, and nuts 16.

The housing 11 is divided into two compartments 17 and 18, compartment 17 enclosing an electric circuit controller (not shown) and compartment 18 housing the buffer 10. The buffer compartment 18 is divided into two interconnecting sections 20 and 21, the horizontal section 20 enclosing the buffer mechanism to be described, and the vertical section enclosing the buffer actuating mechanism; the two sections being interconnected by an opening 22.

A splined shaft 23 is journaled in suitable bearings 24 (Fig. 2) in the housing 11. Fixed to the ends of the splined shaft are treadle supporting arms 26 having fixed thereto, as by bolts 27 and reinforcing clamps 28, an elongated flexible

3

treadle 29 paralleling the track rail 13. The splined shaft 23 passing through the compartment 18 has fixed thereto a depending buffer operating arm 19, the bifurcated lower end of which passes through the opening 22 into the horizontal section 20.

A cylinder 30 is formed in the right-hand end of the horizontal section 20. A piston 31 is slidably received within the cylinder 30 and is connected to the bifurcated end of dependent arm 29 by way of a pin 32 extending transversely of the piston 31. The left-hand end of the piston is formed with an arcuate shoulder 33, for purposes hereinafter appearing, while the right-hand end is provided with a check valve 34 in the longitudinal passage of the piston. The check valve is biased to a closed position by a coil spring 36, the outer end of which is held by a spring retainer 37 fixed to the piston.

The right-hand end of the cylinder 30 is formed with a shoulder 38 serving as a limit stop for the piston 31, while the left-hand end of the cylinder is similarly provided with the shoulder 39. Drain plugs 40 are provided for opposite ends of the cylinder 30, while a filler plug 41 is provided for the right-hand end of the cylinder. The filler plug is formed with a restricted orifice 42 interconnecting the right-hand end of cylinder 30 with the upper section 21. It will be appreciated that the level of the filler plug 41 is below the splined shaft. When a suitable hydraulic fluid is supplied for the buffer mechanism thus far described the horizontal section 20 will be filled and the vertical section 21 only partly filled, the oil level remaining below the splined shaft 23.

Maintenance of the oil level in the buffer mechanism is therefore not dependent on seals for the shaft, or any other seals between moving parts. The construction of the vertical section is such that an expansion chamber is formed above the oil level to take care of any expansion of the oil due to temperature changes. The volume of air therein also provides a cushioning effect in the event excessive pressures are developed on the left side of the piston 31.

The shoulder 33 on the left-hand end of the piston 31 supports a frusto-conical spring disc 43 which is adapted to engage the left-hand shoulder 39 of the cylinder. The left-hand end of the horizontal section 20 is closed by a plug 44, the plug acting as a spring retainer for a coil spring 45. The coil spring is compressed within the section 20 between the plug 44 and the piston 31, to bias the piston to the position shown against the right-hand stop 38 of the cylinder.

As more appropriately detailed in the aforesaid parent application, the depression of the treadle 29 will rotate the splined shaft 23 in a clockwise direction. The piston 31 will thus be moved to the left against the bias of the spring. The movement of the piston 31 by the swing of arm 19 will create a difference in pressure between the left-hand end and right-hand end of the cylinder. Due to the high pressure on the left-hand end of the cylinder, the check valve 34 will open against the bias of the spring 36. The difference in pressure is thereby relieved permitting the piston to move to the left and be brought to a sudden stop by the abutment of the piston 31 and the cylinder shoulder 35. The frusto-conical spring 43 will cushion the shock of impact, thereby preventing any damage to the buffer mechanism.

4

Upon release of the treadle 29, the coil spring 45 will tend to return the piston 31 to its initial position against the stop 38. The increased pressure on the right hand side of the piston due to the return movement will close the check valve 34. The only fluid connection between the two sides of the piston is by way of the restricted passage 42 of plug 41. The return of the piston 31 to its initial position by the spring will thus be retarded for the time interval required for the hydraulic fluid on the right of the piston to pass through the orifice 42.

It will thus be seen that there is provided a novel buffer mechanism in which the several objects of this invention are achieved, and which is well adapted to meet the conditions of practical use.

As various embodiments of the above invention may be made, and as various changes may be made in the embodiment set forth above, it will be understood that all matter herein set forth, or shown in the accompanying drawings, is to be interpreted as illustrative and not in a limiting sense.

Having thus described our invention, what we claim is:

1. In a buffer mechanism, a cylinder, a piston movable within said cylinder, a passage connecting the ends of the cylinder to permit free movement of the piston toward one end of the cylinder, a return spring for said piston, a stop in said cylinder for limiting the free movement of said piston, and a frusto-conical spring disc located on said piston having its periphery projecting toward said stop to absorb shocks due to sudden stopping of the piston by said stop.

2. In a buffer mechanism, a cylinder, a piston movable within said cylinder, a passage connecting the ends of the cylinder to permit free movement of the piston toward one end of the cylinder, said cylinder having an annular shoulder, a circular projection on the end of the piston nearest said one end of the cylinder, an annular frusto-conical spring disc received on said projection and having its periphery projecting toward said shoulder to absorb shocks due to sudden stopping of the piston, and a coil spring having one end abutting said one cylinder end and having its other end encircling said projection and engaging said projection and engaging said spring disc so as to bias the piston for movement toward the other end of the cylinder and to hold the disc in place.
